[57] **CLAIM**

The ornamental design for a blacktop applicator brush and squeegee combination, as shown.

DESCRIPTION

FIG. 1 is a perspective view of a blacktop applicator brush and squeegee combination, showing my new design;

FIG. 2 is a perspective view taken from the opposite side thereof, with the bristle tufts removed for ease of illustration and clarity of disclosure;

FIG. 3 is a front elevational view thereof;

FIG. 4 is a rear elevational view thereof;

FIG. 5 is a side elevational view thereof;

FIG. 6 is a top plan view thereof;

FIG. 7 is a bottom plan view thereof.
